VENDING MACHINE

Isidore Alexander Traversy, Ottawa, Ontario,
CanadaApplication August 7, 1936, Serial No. 94,858
In Canada August 9, 1935

7 Claims. (Cl. 194—68)

This invention relates to vending machines and more particularly to coin controlled vending machines.

Vending machines of this type heretofore proposed have usually been of expensive and complicated construction and moreover have been subject to frequent mishaps in operation, particularly in the delivery of the vended articles.

The present invention has for an object to provide a machine in which such disadvantages have been substantially eliminated and which may be readily constructed in various forms to vend different types of articles. The invention also includes a novel coin changing mechanism.

15 The invention will be described with reference to the accompanying drawings, which illustrate two embodiments thereof and in which

Figure 1 is a sectional side elevation of a machine suitable for vending newspapers, periodicals and the like,

20 Figure 2 is a sectional plan view,

Figure 3 is a front view,

Figure 4 is an enlarged partial section on line 4—4 of Figure 2,

25 Figure 5 is an enlarged partial section on line 5—5 of Figure 2,

Figure 6 is an enlarged plan view of the controlling mechanism,

Figure 7 is a front view of a machine suitable 30 for vending packaged goods such as chewing gum, chocolate bars, sanitary pads and tampons and the like,

Figure 8 is a sectional side elevation of the machine shown in Figure 7,

35 Figure 9 is a section on line 9—9 of Figure 8,

Figure 10 is a section on line 10—10 of Figure 9, and

Figure 11 is a section on line 11—11 of Figure 9.

40 Referring to Figures 1 to 6, inclusive, 1 is a box or casing provided with a water-tight cover 2, a false bottom or horizontal partition 1' suitably secured to the walls of the box adjacent the bottom thereof and a delivery opening 7 extending across the front of the box. The casing 1 contains articles to be vended which rest on a tray 66 supported adjacent one end by a stand 67 mounted on the partition 1', the other end being curved downwardly as shown in Figure 1 and ex-

45 tending into opening 7 where it is supported. An article ejecting mechanism is mounted on partition 1' and includes an operating rod 51 which extends through a hole in the front of the box and is provided with a handle 51'. A locking bar 52 for the rod 51 is also mounted on the parti-

tion 1' adjacent the front of the box and is adapted to be coin-actuated through extensions 21 and 34 of the bar which have engagement with coin receivers 8 and 9, respectively, in a manner to be later described. A guiding member or plate 5 69 rests on the stack of articles 68 and has sliding engagement with the side walls of the box by means of grooves 70 formed in the side walls of box 1 and which are engaged by the ends of a rod 71 mounted adjacent the front edge of 10 member 69. As shown, the member 69 is curved downwardly towards the opening 7.

The cover 2 is effectively secured to the box by means of lugs 3 adapted to slidably engage grooves 4 formed on the sides of the box by 15 means of strips 5. Suitable locking means 6 for the cover may be provided.

The delivery opening 7, as shown, is formed by making a horizontal cut and two short vertical cuts in the wall of box 1 and bending the 20 depending strip upwardly whereby a protective drip trough is formed over the opening.

Coin receivers 8 and 9 are supported on partition 1' and the forward portions thereof extend through openings in the front wall of the 25 box 1.

Coin receiver 8 is formed with a base plate 10 and an upper plate 11 separated by narrow strips 12 extending along the sides thereof to form a coin passage 13, the plate 10, strips 12 and plate 11 being secured together in assembled relation by any suitable means such as bolts, not shown, and a finishing moulding or strip 14 may be placed along the exposed edges as shown. The exposed portion of upper plate 11 is provided 30 with a coin receiving opening 17 and a slot 15, through which projects a handle 19 of a coin positioning member 18 slidably mounted in passage 13. A spring 20 normally holds the member in the position shown in Figure 2. The end of extension 21 extends, as shown, into coin passage 13 adjacent the inner end thereof. The extension 21 rests on a support 23 which may be a portion of plate 10.

Coin receiver 9 is similar in construction to 45 coin receiver 8 and includes a base plate 24, upper plate 25, strips 26, coin passage 27, moulding 28, coin receiving opening 31, a coin positioning member 32 in passage 27 with a handle 33 which extends through a slot 29 in the exposed portion 50 of upper plate 25. A spring (not shown) may also be provided to normally hold the member 32 in the position shown in Figure 2. The end of the extension 34 extends into passage 27 and is provided with a pin 34'. The pin 34', as 55

shown, extends upwardly in a lateral slot 35 formed in upper plate 25 whereby the pin 34' with extension 34 may be moved laterally.

A coin changing mechanism is associated with 5 coin receiver 9 and includes a coin chamber 45, open at the bottom, mounted on a housing 44 adapted to slidably receive a coin selector plate 40 and a coin delivery plate 46. Delivery plate 46, it will be noted, rests on partition 1' and 10 slides into the housing 44 below selector plate 40. Springs 43 and 47, respectively, normally hold selector plate 40 and delivery plate 46 in the positions shown in Figure 2. Selector plate 40 and delivery plate 46 are provided with coin 15 openings 49 and 50, respectively, which are adapted to register with the coin chamber opening but are normally held out of registry therewith as shown in Figure 2. A coin opening 48 is formed in partition 1' and is in registry with 20 opening 50 when delivery plate 46 is in its normal position. A coin returning chute 48' is connected to opening 48. Coin selector plate 40 is adapted to be moved into registry with the coin chamber opening by an actuating bar 36 through 25 a lever 39 mounted on a pivot 39' secured to partition 1'. As shown, one end of lever 39 is pivoted to bar 36 and the other end rests on selector plate 40 and has engagement therewith by means of a pin 41 on plate 40 and a notch 42 in link 39. 30 Actuating bar 36 extends into coin passage 27 and is provided at its end with a pin 36', which extends upwardly in a lateral slot 37 opposite slot 35, being adapted for lateral movement therein. The other end of bar 36 is connected to a spring 35 38 which normally holds the bar in the position shown in Figures 2 and 5.

Base plate 24 is suitably cut away to receive extension 34 and actuating bar 36.

The article ejecting mechanism includes a 40 transverse bar 56 connected to the inner end of operating rod 51 and provided with flanges 57 at either end in which are mounted upright rods 58 carrying in sliding engagement therewith a cross bar 62 provided with article-engaging pick devices 63 which are pivotally mounted in flanges 64 secured to bar 62 and extend through slots 72 in the guide member 69.

Coin removing fingers 59 are keyed or otherwise fixed to a shaft 59' mounted for rotation in bar 56 and are adapted, when in coin removing position, to project into coin passages 13 and 27, respectively, through slots 16 and 30 formed in upper plates 11 and 25 of coin receivers 8 and 9, respectively. As shown, the bar 56 is cut away 55 to suitably receive the fingers 59. Means are provided for preventing engagement of the coin-gripping ends of fingers 59 with coin passages 13 and 27 and comprise a pin 60 carried at the end of one finger 59 and adapted for cooperation 60 with a strip 61 secured to plate 11. The inner end of strip 61 is inclined whereby pin 60 may engage the inclined surface and ride along the top surface of the strip. The inner edge of strip 61 is also offset with respect to plate 11 whereby 65 the pin 60, after dropping over the outer end of the strip, may travel in the return direction between the strip 61 and plate 11 with the coin-gripping ends of fingers 59 in engagement with coin passages 13 and 27 through slots 16 and 30, as 70 shown in Figure 4.

Springs 65 connected to bar 56 and the back wall of box 1 tend to hold the article ejecting mechanism in retracted position as shown in Figure 2.

75 Holes 13 are formed in partition 1' adjacent the

inner ends of coin receivers 8 and 9 and communicate with a coin receiving drawer 74 positioned in the space between partition 1' and the bottom of the box. A locking device for drawer 74 consists of a bar 75 slidably mounted in a 5 bracket 76, and having its lower end adapted to engage the inside surface of the back wall of drawer 74 as shown in Figure 1.

Locking bar 22 is provided with a notch 77 adapted to engage corresponding notches 78 in 10 rod 51. A spring 79, which is connected to a post 80 and engages one end of locking bar 22, normally urges the bar to the left as shown in Figure 6 whereby notch 77 will engage one of the notches 78, the normal locked position of bar 22 15 and rod 51 being when rod 51 is in fully retracted position and notch 77 engages the outermost notch 78 in rod 51. A positioning device for bar 22 includes a pin 81 mounted on the under side of bar 22 and extending through a slot 82 in partition 1'. A cross piece 83 is formed on the end of pin 81 and is adapted to slide in a housing 84.

Operating rod 51 is provided with a ratchet mechanism to prevent unauthorized shaking of 25 the bar when in withdrawn position. As shown, ratchet teeth 85 in a strip 86 mounted on bar 51 are adapted for engagement with a tooth 89 pivotally carried at one end of a ratchet lever 87 which is pivotally mounted on a post 88 and connected to bar 22 at its other end. As shown, tooth 89 is pivoted whereby it may swing in a forward direction only and is urged into normal position by spring 90.

Operating rod 51 may also be provided with a 35 positioning device comprising a pin 52 mounted on the under side of rod 51 and extending through a slot 53 in partition 1' and formed with a cross piece 54 adapted to slide in a housing 55 secured to the under surface of partition 1'.

A bell 91 may be mounted on partition 1' and is adapted to be actuated by bar 56 to indicate its fully withdrawn position.

Means for indicating when the machine is empty are provided and may consist of a plate 92 45 adapted to rest on the bottom of article tray 66. Plate 92 is provided with a hinged flap 93 bearing the indication "Empty" and pins 94 slidably mounted in slots 95. The last article in the tray 50 engages pins 94 and when ejected carries with it to opening 17 the plate 92 whereby flap 93 emerges to display the "Empty" sign.

In operation, the articles 68 and guide member 69 are arranged in the box as shown in Figure 1, with the various parts in the positions shown 55 in Figures 1, 2 and 5. The present embodiment is particularly well adapted for the sale of newspapers. It may be assumed, for instance, that coin receiver 8 is adapted to receive three one-cent pieces 8', in return for which a newspaper 60 may be delivered, and that coin receiver 9 is adapted to receive a five-cent piece, in return for which a newspaper and two cents change are delivered. The one-cent pieces are inserted in opening 17 and each is pushed along passage 13 by 65 means of member 18. As the third cent is pushed along the passage the first cent engages the end of extension 21, as shown in Figure 6, and forces locking bar 22 laterally thus disengaging notches 77 and 78. Operating rod 51 may then be withdrawn 70 until the bell 91 rings and carries with it bars 56 and 62 with pick devices 63 and fingers 59. The pick devices 63 positively engage the uppermost newspaper and propel it forward, the guide member 69 guiding the newspaper towards 75

the opening 7. When the operating rod has reached its outermost withdrawn position, the newspaper will have been ejected through opening 7 and fingers 59 will have been carried over slots 16 and 30 (pins 60 having engaged strip 61 as shown in Figure 4) and the ends thereof will have dropped into the slots as shown in Figure 6 and in dotted lines in Figure 4. The rod 51 may then be returned to its retracted position and finger 59 in its return movement will engage the coins in slot 16 as shown and cause them to drop through hole 73 into drawer 74. Removal of the coins permits locking bar 22 to return to normal position.

It will be noted that when bar 22 is moved out of locking engagement with rod 51, ratchet lever 87 will swing into engagement with the ratchet teeth 85 thus allowing movement of bar 51 in outward direction only, whereby unauthorized shaking of the bar is prevented. As shown in Figure 6, a short portion of the inner end of strip 86 is not provided with teeth whereby bar 51 may be moved in a reverse direction a distance sufficient to enable the coins to be removed by finger 59, when locking bar 22 is again allowed to engage rod 51 whereby notches 77 and 78 engage to allow movement of the rod 51 in an inward direction only. Thus at practically all times the rod 51 is movable in one direction only.

When a five-cent piece is placed in opening 31 of coin receiver 9 and pushed into position by the member 32, it forces pins 34' and 36' of extension 34 and bar 36 apart, as shown in Figure 6, thus causing locking bar 22 to be moved out of locking position with rod 51 whereby a newspaper may be ejected by the mechanism. Actuating bar 36 is moved into the position shown in Figure 6 and actuates lever 39 to move coin selector plate 40 whereby opening 49 therein registers with the opening in coin chamber 45. Coin chamber 45 is charged with a suitable supply of one-cent pieces and coin selector plate is of a thickness of, say, two coins, whereby two coins may drop from chamber 45 into opening 49. The coin changing mechanism remains in this position until bar 56 has arrived approximately at its outermost position, at which time it strikes the flange 46' of coin delivery plate 46, which is of the same thickness as coin selector plate 40, and carries plate 46 forward a short distance whereby opening 50 in plate 46 registers with opening 49 and whereby the two coins selected by plate 40 may drop into opening 50. When operating rod 51 is returned to retracted position, spring 47 returns plate 46 to its normal position whereby openings 50 and 48 register and the two coins are permitted to drop into chute 48' and be removed by the newspaper purchaser, thus completing the transaction. The five-cent piece in slot 30 is of course engaged by finger 59 and dropped into drawer 74.

Obviously, coin receiver 8 may be adapted for receiving any suitable number of coins in return for which a newspaper may be delivered and the coin changing mechanism in association with coin receiver 9 may be adapted to carry out various coin changing operations.

Moreover this embodiment of the machine may be easily adapted for vending various types of periodicals as well as numerous other articles.

Referring to the embodiment shown in Figures 7 to 11, inclusive, 101 is a box or casing provided with a cover member 102, a horizontal partition 101' and a delivery opening 103 at the front of the box. A locking lug 104 adapted to extend

through a slot in the cover 102 may be provided on the box. The box 101 contains articles 105 to be vended which rest on a platform 106 supported on the back wall of the box. A delivery chute 107 leads from platform 106 to opening 103 as shown.

An article ejecting mechanism is mounted on partition 101' and includes an operating rod 108 which extends through a hole in the front of the box and is provided with a handle 108'. A locking bar 109 for the rod 108 is slidingly mounted by means of brackets 109' on the partition 101' adjacent the front of the box.

Coin receiving chutes 110, 111 and 112 are supported on the inside front wall of the box 101 and communicate with corresponding openings in the wall.

Coin chute 110 is arranged to deposit coins as indicated at 110' upon a plate 113 provided with side strips 114 to form a coin passage thereon. The plate 113, which is positioned immediately above the operating rod 108 and the inner end of which abuts the locking bar 109, is supported by means of the side strips 114 from the chute 110 as shown. A coin positioning member 115 extends through an opening in the wall of box 101 and its inner end 116 slidingly engages the surface of plate 113 whereby actuation of the member will force a coin along the passage thereon. A spring 117 returns the member 115 to normal position defined by a stop 118 on the member.

Coin chutes 111 and 112 are arranged to deposit coins as indicated at 111' and 112' upon the upper surface of partition 101' in coin passages defined thereon by means of pairs of strips 119 and 119' respectively. Coin positioning members 120 and 120' extend through openings in the wall of box 101 below partition 101' and are provided with forked inner ends adapted to engage the lower ends of pins 121 and 121' respectively extending through and carried by strips 122 and 122' slidingly mounted in brackets 123 and 123' on the under surface of partition 101'. The upper ends of pins 121 and 121' extend through slots 124 and 124' formed in partition 101' and into the coin passages on the upper surface thereof. Thus actuation of the members 120 and 120' will force coins in the passages along the same. Springs 125 and 125' return the strips 122 and 122' to normal position abutting the wall of box 101. Springs 126 and 126' return the members 120 and 120' to normal position defined by stops 127 and 127' formed thereon.

Locking bar 109 is provided with a notch 128 adapted to engage corresponding notches 129 in rod 108. A spring 130, which is connected to partition 101' and engages one end of locking bar 109, normally urges the bar to the left as shown in the Figure 9 whereby notch 128 will engage one of notches 129, the normal locked position of bar 109 and rod 108 being when rod 108 is in fully retracted position and notch 128 engages the outermost notch 129 in rod 108 as shown in Figure 9. Springs 130' are provided to return rod 108 to retracted position. Coin receiving slots 131, 132 and 133, corresponding to but not in exact alignment with the coin passages of chutes 110, 111, and 112, respectively, are formed in the locking bar 109. The right hand side walls of slots 131, 132 and 133, as shown in Figure 9, are curved to facilitate the positioning of coins therein and it will be noted that forcing of a coin into one of said slots by means of one of members 115, 120 or 120' will 75

move the bar 108 to the right out of locking engagement with operating rod 108 whereby it may be pulled outwardly.

Article ejecting mechanism includes a transverse member 134 adapted to slide on platform 106 and carried by a supporting structure 135 mounted on the inner end of operating rod 108. The articles 105 are housed in an open-ended magazine 136 secured to the back wall of box 101 and are deposited onto platform 106 from the lower end thereof, which is spaced from the platform a distance approximately the thickness of one article whereby the lowermost article may be engaged by the transverse member and moved forwardly of the platform 106. In operation a second article 105' is placed adjacent the lowermost article as shown in Figure 8 whereby movement of the lowermost article will cause the article 105' to fall into the delivery chute 107. A pair of article guiding members 137 may be provided on the platform 106.

Coin changing mechanisms are associated with coin chutes 111 and 112 and include open-ended coin chambers 138, 138' mounted on pairs of strips 139, 139' secured to partition 101' arranged to slidably receive therebetween coin selecting and delivery plates 140, 140'. The plates 140, 140' are provided with holes 141, 141' corresponding with and normally in registry with the lower open ends of coin chambers 138, 138'. Openings 142, 142' are formed in partition 101' beneath plates 140, 140' and somewhat to the right of coin chambers 138, 138' as shown in Figure 9. The plates 140, 140' are maintained in their normal position by means of levers 143, 143' pivoted at one end to the plates 140, 140' and pivotally mounted at 144, 144' on partition 101'. The other ends of levers 143, 143' extend into coin receiving slots 132 and 133, respectively and are curved to fit against the right curved walls of said slots. The levers 143, 143' are maintained in normal position by means of springs 145, 145' and stops 146, 146'. It will be noted that inserting a coin in either of slots 132 or 133 will cause the respective levers 143, 143' to move one of plates 140, 140' to the left whereby coins selected by the hole in the plate will be moved over opening 142 or 142' and allowed to drop through the same, coin returning chutes 147, 147' being provided in communication therewith.

Coin are removed from the slot 131 by means of a coin removing finger 148 pivotally carried by a support 149 secured to operating rod 108. The finger 148 is held against a stop 150 by means of a spring 151 whereby it may ride over a coin in slot 131 on outward movement of rod 108 but on inward movement of rod it will engage the coin and carry it backward to drop into an opening 152 formed in partition 101'.

Coin are removed from slots 132 and 133 by means of the pins 121, 121' means being provided to move the same backwardly along the slots 124, 124' a distance sufficient to remove the coins from the slots 132, 133 and deposit the same into openings 153, 153' formed in partition 101'. This means comprises a pair of levers 154, 154' pivotally mounted at 155, 155' on the lower surface of partition 101' and having hooked outer ends engaging the lower end of pins 121, 121' respectively. The inner ends of levers 154, 154' are also hooked and engage a pin 156 carried on the lower surface of operating rod 108 and extending through a slot 157 in the partition 101'. It will be noted that forward move-

ment of rod 108 will cause the levers 154, 154' to move the pins 121, 121' backwardly.

A coin receiving drawer 158 adapted to receive coins deposited in openings 152, 153 and 153' is positioned in the lower portion of box 5 101 and is provided with a locking device 159.

Any suitable means may be provided for indicating when the machine is empty.

Operation of the machine will be apparent from the foregoing description. Coin chute 110 is 10 adapted to receive a coin of the exact value of the article to be vended, for instance, a five-cent piece. Coin chute 111 is adapted to receive, for instance, a ten-cent piece, which when positioned to unlock bar 108, will also actuate lever 143 to return, through the returning chute 147, a five-cent piece. Coin chute 112 is adapted to receive, for instance, a twenty-five cent piece, which, when positioned to unlock bar 108, as indicated in dotted lines, will also actuate lever 143' to return, through the returning chute 147', two ten-cent pieces.

As in the other embodiment, the machine may be readily adapted for various coin changing operations as well as for vending various types 25 of articles.

Any suitable type of slug detectors may be readily incorporated in the machines described.

I claim:

1. In a vending machine having a coin passage, an article ejecting mechanism and an operating rod therefor, coin-controlled means for locking the operating rod against movement comprising a slidable locking bar having a coin-engaging portion extending into the passage, means for forcing a coin deposited in the passage into contact with said portion to actuate the locking bar to unlock the operating rod for movement, a coin receivable having an opening adjacent the end of the passage, means adapted to engage a coin in the passage and move the same to the end of the passage and into said opening, and means carried by said operating rod and adapted on movement of the rod to actuate said last-mentioned means.

2. In a vending machine having a plurality of coin passages, a slidable locking bar having coin-engaging portions extending into each of the passages, means associated with each passage for forcing a coin deposited therein into contact with the coin-engaging portion of the bar in the passage to actuate the locking bar, and coin changing mechanism associated with at least one of the passages including an actuating lever having a coin-engageable arm extending into the passage in adjacent relation to the coin-engaging portion of said bar whereby said coin may engage said arm simultaneously with engagement with said portion and actuate the lever.

3. In a vending machine having a plurality of coin passages, an article ejecting mechanism and an operating rod therefor, coin-controlled means for locking the operating rod against movement comprising a slidable locking bar extending transversely through said passages and having coin slots communicating with said passages but normally out of registry therewith, one side of each slot having a coin-engaging surface, means associated with each passage for forcing a coin deposited therein into contact with the coin-engaging surface of the communicating slot to actuate the locking bar to unlock the operating rod for movement, and coin changing mechanism associated with at least one of the passages including an actuating lever having a coin-engage- 70 75 80 85 90 95 100 105 110 115 120 able arm extending into the passage in adjacent relation to the coin-engaging surface of the communicating slot whereby said coin may engage said arm simultaneously with engagement with said surface and actuate the lever.

- 5 4. In a vending machine having a coin passage, an article ejecting mechanism and an operating rod therefor, coin-controlled means for locking the operating rod against movement comprising a slidable locking bar having a coin-engaging portion extending into the passage, means for forcing a coin deposited in the passage into contact with said portion to actuate the locking bar to unlock the operating rod for movement, means adapted to engage the coin and move the same out of contact with said portion, and means carried by said operating rod and adapted on movement of the rod to actuate said last-mentioned means.
- 10 10 5. In a vending machine having a coin passage, an article ejecting mechanism and an operating rod therefor, coin-controlled means for locking the operating rod against movement comprising a slidable locking bar, a coin-engageable arm connected to said bar for actuating the same, said arm extending into the passage, means for forcing a coin deposited in the passage into contact with said arm to actuate the locking bar to unlock the operating rod for movement, means
- 15 25 30 adapted to engage the coin and move the same out of contact with said arm, and means carried by said operating rod and adapted on movement of the rod to actuate said last-mentioned means.

6. In a vending machine having a coin pas-

sage, an article ejecting mechanism and an operating rod therefor, coin-controlled means for locking the operating rod against movement comprising a slidable locking bar extending transversely through said passage and having a coin slot communicating with said passage but normally out of registry therewith, one side of the slot having a coin-engageable surface, means associated with the passage for forcing a coin deposited therein into contact with the coin-engageable surface of the slot to actuate the locking bar to unlock the operating rod for movement, means for moving the coin out of said slot, and means responsive to movement of the operating rod for actuating said last-mentioned means.

7. In a vending machine having a plurality of coin passages, an article-ejecting mechanism and an operating rod therefor, coin-controlled means for locking the operating rod against movement comprising a slidable locking bar, a plurality of coin-engageable arms connected to said bar, each arm extending into a corresponding coin passage and being adapted to actuate the locking bar, means for forcing a coin deposited in the passage into contact with the arm therein to actuate the locking bar to unlock the operating rod for movement, and coin changing mechanism associated with at least one of the passages including a lever extending into the passage in adjacent relation to the arm therein whereby said coin may engage said lever simultaneously with engagement of said arm.

ISIDORE ALEXANDER TRAVERSY.
